UNITED STATES PATENT OFFICE.

PHILLIPS ABBOTT, OF BROOKLYN, ASSIGNOR, BY MESNE ASSIGNMENTS,
TO JOSEPH RECKENDORFER, OF NEW YORK, N. Y.

LEAD-PENCIL.

SPECIFICATION forming part of Letters Patent No. 248,549, dated October 18, 1881.

Application filed August 9, 1880. (No model.)

To all whom it may concern:

Be it known that I, PHILLIPS ABBOTT, of the city of Brooklyn, State of New York, have invented a new and useful Improvement in 5 Lead-Pencils, which is fully set forth in the following specification, reference being had to the accompanying drawings, in which—

Figure 1 shows a vertical section of the said pencil, and Fig. 2 an enlarged section, showing the lead, the outside and the inside tubes, and the lead-holding device; Fig. 3, another form of lead-holding device.

Prior to my invention various means have been used for holding the lead in pencils of the 15 class in which the lead is movable, and my invention is an improvement in pencils of this class.

In Fig. 1, *a* is an outer tube, and *b* an inner one, which constitute the handle of the pencil, 20 and *c* is a spring which is attached to the inner and outer tubes by any suitable well-known attachments, and its effect is to project the inner tube from the outer one at the end opposite the point of the pencil; and *d* is the lead-holding device, which is the peculiar feature of this invention.

The construction of this pencil is as follows:

The two tubes are so constructed that the inner one slips very freely and easily into the 30 outer one. At the point *e* in the side of the inner tube, and through a slot therein, I introduce the lead-holding device *d*, which is seen enlarged in Fig. 2. This device *d* is pivoted on the side of the inner tube, as seen at *f*, Fig. 32, and operates or swings through the slot before mentioned cut in the side of this inner tube. The end of this lead-holding device *d*, which is outside of the inner tube, runs tapering off from the part through the pivot passes 35 until it comes to the surface of the inside wall of the outer tube, as is seen at *g*, Fig. 2, and it is received into either a hole or some other depression made in the wall of the outer tube itself, or made in a piece of metal soldered upon 40 the inside of the outside tube.

The inner end of the lead-holding device *d*, which swings into the inner tube, is bent somewhat in the shape of a letter, *L*, the arm of the *L* running toward the point of the pencil, as 45 seen in Figs. 1 and 2, and in cross-section this arm is made somewhat rounding in the direc-

tion in which the tube in which it operates is rounding; or, in other words, in the form of a half-tube, so that it may better catch and hold the lead. In the surface of this arm of 55 the *L*-shaped lead-holding device *d*, which comes in contact with the lead, I form little teeth, which are inclined toward the point of the pencil, so that they will readily catch in the lead for holding it. The front edge of this device *d* may be bent slightly inwardly and made sharp, so that it will catch in and hold the lead 60 without any teeth.

I prefer to make the tubes of wood, metal, paper, rubber, or celluloid; but they may be 65 made of any suitable material. The lead-holding device I prefer to make of metal, preferably hard brass; but it may be made, also, of other suitable material.

The pivoting of the holding device may be 70 made in any suitable manner, either by a regular pivot or by a latch or any other operative joint by which the necessary swinging action of the lead-holding device can be obtained.

The operation of my improved pencil is as 75 follows: When the inner tube is pressed into the outer one as far as it will go by pressure applied to the exposed end of the inner tube, by which pressure, also, the spring *c* is compressed, the lead-holding device *d* is, by reason of the connections between it and the tubes, 80 made to swing out of the inner tube, or nearly out of it, depending upon the nicety in construction of the several parts. The lead can then be introduced into the hole in the point 85 of the outer tube of the pencil, as seen at *k*. It then passes into the open end of the inner tube at *l*, and then passing the lead-holding device *d* it can slip into the inner tube till it strikes its closed end, and thus the lead, when allowed 90 to slip entirely within the tubes, will be completely protected from liability to fracture. When, however, the pencil is to be used the pressure is withdrawn from the end of the inner tube while the lead is still somewhat projecting from the point of the pencil *k*. The spring 95 *c* then immediately acts to throw the inner tube out of the end of the outer one, and by the action of the connections between the lead-holding device and the inner and outer tubes the 100 part of the lead-holding device marked *d'* is made to swing in toward the center of the in-

side tube, and in its passage it comes in contact with the lead and prevents it from moving, not only by the resistance of the lead to the cutting action of the front edge of the device 5 $d d'$, and to the scratching action of the little teeth or roughnesses before mentioned, but also and prominently by the clamping or squeezing effect to which I subject the lead between the clamping device $d d'$ and the opposite 10 side of the inner tubes, and the more pressure there is applied to the point of the lead the more the holding device $d d'$ will squeeze the lead and hold it firmly; and I am careful, in proportioning my pencil, to have the relative 15 sizes and degrees of motion of the parts such that I will secure this clamping effect on the lead. It is to be noticed that the location of the confining-hole for the end of the L-shaped holder and the location of the pivot in the core 20 of the pawl must be such that the holding device will be swung out of the inner tube when the tubes are telescoped.

Instead of an inside tube there may be used a ring or short section of a tube at the part 25 where the holder d is situated, and the remainder of the tube be supplied by one, two, or more connecting-rods connecting the spring c and the holder $d d'$. The spring may also be placed at some other point than at the end of 30 the inner tube, and the outside tube may be not so long as the inside tube.

In conclusion, I state that I do not claim, broadly, a lead and crayon holder having a lead-grasping jaw or contrivance inside of and connected with the sheath extending into the 35 interior of the longitudinally-movable lead-containing tube through an opening therein, so as to have contact with the lead and operated by the tube according to the direction of its movement to clamp and release the lead; nor do I 40 claim, broadly, the combination of the foregoing instrumentalities with a pressure-cap and a retracting-spring.

Having thus described my invention, what I claim is—

In a lead-pencil or similar utensil, a lead-holding device pivoted to the inner tube and with an extending end which engages in a depression or other confining device on the outer tube, the parts being so adjusted and located 50 that when the tubes are slid past one another the inner part of the lead-holding device will be thrown outwardly away from or inwardly toward the center of the inner tube, according as the tubes are slid on one another in one direction or the other, substantially as and for the purposes set forth.

PHILLIPS ABBOTT.
